DESIGN FOR A HOLDER FOR CRACKERS AND CHEESE

James W. Warren, Los Angeles, Calif.

Application March 9, 1940, Serial No. 90,787

Term of patent 14 years

To all whom it may concern:

Be it known that I, James W. Warren, a citizen of the Dominion of Canada, residing at Los Angeles, in the county of Los Angeles and State of California, have invented a new, original, and ornamental Design for a Holder for Crackers and Cheese, of which the following is a specification, reference being had to the accompanying drawing, forming a part thereof.

Fig. 1 is a top plan view of the holder for crackers and cheese, showing my design; and

Fig. 2 is a side elevational view thereof.

I claim:

The ornamental design for a holder for crackers and cheese, substantially as shown.

JAMES W. WARREN.
